US0D1103980S

(12) **United States Design Patent** (10) **Patent No.:** **US D1,103,980 S**
(45) **Date of Patent:** **** Dec. 2, 2025**

(54) **INTELLIGENT ACCESS CONTROL DEVICE**

(71) Applicants: **THALES DIS FRANCE SA**, Meudon (FR); **10 SQUARED LTD**, York (GB)

(72) Inventors: **Ivan Minaya**, Meudon (FR); **Yann Tremeac**, Meudon (FR); **Françoise Bergasse**, Meudon (FR); **Pierre Luc Arnaud**, Meudon (FR); **Gary Steele**, York (GB); **Pat Holbrough**, York (GB); **Tom Langford**, York (GB); **Matthew Baxter**, York (GB)

(73) Assignees: **THALES DIS FRANCE SAS**, Meudon (FR); **10 SQUARED LTD**, York (GB)

(**) Term: **15 Years**

(21) Appl. No.: **29/835,608**

(22) Filed: **Apr. 20, 2022**

(30) **Foreign Application Priority Data**

(57) **CLAIM**

The ornamental design for an intelligent access control device as shown and described.

DESCRIPTION

FIG. 1 is a left side view of a first embodiment of an intelligent access control device showing our new design; FIG. 2 is a front view thereof; FIG. 3 is a right side view thereof; FIG. 4 is a back view thereof; FIG. 5 is a front, right, top perspective view thereof; FIG. 6 is a left side view of a second embodiment of the intelligent access control device; FIG. 7 is a front view thereof; FIG. 8 is a right side view thereof; FIG. 9 is a back view thereof; and, FIG. 10 is a front, right, top perspective view thereof. The broken lines in the drawings depict portions of the intelligent access control device that form no part of the claim.

1 Claim, 10 Drawing Sheets
